His Attorney.

UNITED STATES PATENT OFFICE

2,422,428

MULTIFLASH LAMP

Henry Herbert Magdsick, East Cleveland, Ohio,
assignor to General Electric Company, a corpora-
tion of New York

Original application July 5, 1943, Serial No.
493,519. Divided and this application February
21, 1944, Serial No. 523,237

5 Claims. (Cl. 67—31)

1

My invention relates to lamps and its principal object is to provide multiflash lamps for photographic purposes. Further objects and advantages of my invention will appear from the following detailed description of species thereof and from the appended claims.

In the drawing accompanying and forming part of this specification, species of my invention are shown in which Fig. 1 is a bottom plan view of one species of my multiflash lamp with a portion of the lamp base broken away to show the stem portion of a bulb; Fig. 2 is a similar view of another species of my multiflash lamp; and Fig. 3 is a side-elevational, fragmentary view of a support carrying electrical contacts for the multiflash lamps shown in Figs. 1 and 2. Like reference numerals denote like parts in the figures.

Referring to Fig. 1 of the drawing, the species of multiflash lamp 40 illustrated comprises a common base 41 circular in shape and of electrically insulating material, such as fiber, hard rubber, or an electrically insulating, moldable plastic. Said base 41 has a plurality of bulbs 42 permanently secured therein and projecting radially from the peripheral portion thereof. The bulbs 42 are the same in structure, are of ellipsoidal shape and are filled with a combustible material, such as shredded foil (indicated by the light lines in the bulb the internal structure of which is shown in the drawing), and a supporter of combustion, such as oxygen. The combustible material, when ignited, produces a flash of actinic light and is ignited by an ignition means comprising a tungsten filament connected across a pair of current inlead wires 43 and 44 sealed into the stem 45 of the bulbs 42. Such bulbs are disclosed in U. S. Patent No. 2,306,563, issued December 29, 1942, to Marvin Pipkin.

The inlead wire 43 of each of the bulbs 42 is connected to a common, external, center ring contact 46 on the base 41. A plurality of equally spaced contacts 47, one for each of the inleads 44, are disposed adjacent the peripheral portion of the base 41. The center portion of the base 41 has a passage therethrough defined by a metal tube 48 of double bore. The larger-diameter portion of the tube 48 engages with the ring contact 46 on the base 41 and has a pair of diametrically opposed slots 49. A shoulder 50 is provided where the double-bore tube 48 changes in diameter.

The species of multiflash lamp 40 illustrated in Fig. 2 of the drawing is similar to that shown in Fig. 1 except for the provision of a plurality of contacts 51 in place of the single, center ring

2

contact 46. The contacts 51 are disposed at equally spaced positions in a ring around the center of the circular base 41. The double-bore tube 48 of this embodiment may consist of the same electrically insulating material as base 41 and may be formed as an integral part thereof.

The lamps 40 shown in Figs. 1 and 2 may be rotated, as by the lamp holder 52 shown in Fig. 3 of the drawing, in the common plane of the bulbs 42 for successively connecting said bulbs 42 across a pair of contacts connected into an electrical circuit comprising a power source capable of igniting the bulbs 42. The holder 52 comprises a stationary sleeve 53 which accommodates a spindle 54 electrically insulated from said sleeve 53 and rotatable therein. The sleeve 53 supports a spring contact 55 which successively engages contacts 47 on rotation of the lamps 40. The spindle 54 projects beyond the end of sleeve 53 and carries a circular spring contact 56 which, as shown in Fig. 3 engages the ring contact 46 of the lamp 40 shown in Fig. 1. Said contact 56 is large enough in diameter to engage contacts 51 of the lamp shown in Fig. 2 when said lamp is mounted on holder 52. The circular contact 56 rotates with spindle 54, is spaced from the contact 55 and is electrically insulated from the sleeve 53 by the perforated disc 57 of electrically insulating material. The contact 56 has a central, cylindrical portion (not shown) which engages with and extends a short distance along the spindle 54 in the direction of a spring wedge 58 secured to the end portion of spindle 54. The said cylindrical portion of contact 56 is provided with a ridge-like protuberance which serves as a key engaging with one of the slots 49 of the tube 48 of lamp base 41 to rotate the lamps 40 when the spindle 54 is rotated.

A lamp 40 is mounted on the lamp holder 52 by placing the portion of larger diameter of the tube 48 over the end of spindle 54 and wedge 58, moving the lamp base 41 longitudinally of said spindle 54 in the direction of contact 56 to compress wedges 58 and until the key enters a slot 49 and the cylindrical portion of contact 56 abuts against the shoulder 50 of the tube 48. The lamp 40 is then clamped between the spring wedge 58 and the cylindrical portion of contact 56 and the contact 56 engages with the ring contact 46 or the contacts 51, depending on which species of lamp 40 is being used. The spindle 54 may then be rotated to bring one of the contacts 47 into engagement with the contact 55 on the stationary sleeve 53 to connect a bulb 42 across said holder contacts 55 and 56.

The contacts 55 and 56 may be connected through the sleeve 53 and the spindle 54, respectively, into a circuit including a source of electrical energy, such as a conventional flashlight battery, capable of igniting the bulbs 42 when the circuit is closed by a conventional manual or automatic switch. A conventional slip-ring contact may be used for the rotatable spindle 54.

The holder 52 may be mounted on a support which grips the sleeve 53 to support the holder 52 in such position that the bulb 42 connected across the holder contacts 55 and 56 is in effective relation to a reflector for the actinic light emitted by the said bulb 42 when flashed. The spindle 54 may be equipped with a turnable means and an indexing apparatus for advancing and temporarily holding successive bulbs 42 in position to be flashed.

This application is a division of my copending application Serial No. 493,519, filed July 5, 1943, now Patent Number 2,404,970, issued July 30, 1946, and which is assigned to the assignee of this application.

What I claim as new and desire to secure by Letters Patent of the United States is:

1. A multiflash lamp unit comprising a common base and a plurality of flash bulbs radially mounted in a common plane and recessed into said base and permanently secured therein, each of said bulbs having leading-in wires extending therefrom, said base having a plurality of spaced, electrical contacts connected to said wires and so arranged on said base that rotary displacement of said base in said common plane is effective for successively connecting said bulbs to an energizing circuit for igniting said bulbs in sequence, said leading-in wires extending from said bulbs to their respective contacts and being connected directly thereto.

2. A multiflash lamp unit comprising a common cylindrical base having an end wall and an axial shaft-receiving passage, a plurality of flash bulbs recessed into and permanently secured to said base and extending radially outward therefrom, each of said bulbs containing an ignition filament, contact means arranged annularly on the exterior surface of said end wall around said passage, and a plurality of contacts arranged in a circle on the said exterior surface of said end wall outside said annularly arranged contact means, with means electrically connecting one end of each of said filaments to said annularly arranged contact means, and means electrically connecting the other end of each of said filaments to one of the circularly arranged contacts.

3. A multiflash lamp unit comprising a common hollow cylindrical base shell having an end wall and an axial shaft-receiving passage, a plu-

rality of flash bulbs recessed into and permanently secured to said base and extending radially outward therefrom, each of said bulbs having a pair of lead-in wires extending therefrom interiorly of the said base shell, contact means arranged annularly on the exterior surface of said end wall around said passage, and a plurality of contacts on the said exterior surface of said end wall arranged concentrically with the first-mentioned contact means, one of the lead-in wires of each of said flash bulbs extending directly to said first-mentioned contact means and being connected thereto, the other lead-in wire of each of said bulbs extending directly to one of the second-mentioned contacts and being connected thereto.

4. A multiflash lamp unit comprising a common hollow cylindrical base shell having an end wall and an axial shaft-receiving passage, a plurality of flash bulbs recessed into and permanently secured to said base and extending radially outward therefrom, each of said bulbs having a pair of lead-in wires extending therefrom interiorly of the said base shell, and two sets of separate contacts arranged concentrically on the exterior surface of said end wall around said passage, there being a pair of such contacts, one contact from each set, corresponding to each flash bulb, each of the lead-in wires of each flash bulb extending directly to one of the contacts of the corresponding pair of contacts and being connected thereto.

5. A multiflash lamp unit comprising a common cylindrical base of electrically insulating material having an axial shaft receiving passage, electric contacts arranged in spaced relation around said passage for successive engagements on rotation of said unit with stationary contact means of an electric ignition circuit for the lamps, and a plurality of flash bulbs recessed into and permanently secured to said base and extending radially outward therefrom, each of said bulbs having lead-in wires extending therefrom and into direct and permanent engagement with said base contacts for conducting current from said contacts to said lamps.
